DESIGN FOR A BOTTLE

Jerome L. Wiener, Chicago, Ill., assignor to Beau Peep Products, Chicago, Ill., a partnership composed of Jerome L. Wiener and Frank M. Conklin

Application August 15, 1938, Serial No. 79,342

Term of patent 14 years

To all whom it may concern:

Be it known that I, Jerome L. Wiener, a citizen of the United States, residing at Chicago, in the county of Cook and State of Illinois, have invented a new, original, and ornamental Design for a Bottle, of which the following is a specification, reference being had to the accompanying drawing forming a part thereof.

In the drawing:

I claim:

The ornamental design for a bottle, substantially as shown.

JEROME L. WIENER.
